UNITED STATES PATENT OFFICE

2,580,454

COMBINATION DRAWING DIE AND STRIPPER

Clarence Walton Musser, Philadelphia, Pa.

Application March 29, 1946, Serial No. 658,188

9 Claims. (Cl. 113—50)

(Granted under the act of March 3, 1883, as amended April 30, 1928; 370 O. G. 757)

1

The invention described herein may be manufactured and used by or for the Government for governmental purposes, without the payment to me of any royalty thereon.

My invention relates to the production of mechanical draw pieces by conventional "punch and die" techniques and it has special reference to means for stripping a draw piece (such as an ammunition primer cup) from the punch after it has passed through a drawing die.

Broadly stated the object of my invention is to provide a die which is capable of performing a dual function of drawing cup-like pieces and thereafter positively stripping them from the draw punch.

A more specific object is to eliminate the need for separate stripping means in supplement to normal punch and die drawing apparatus.

Another object is to provide means for stripping draw pieces from the punch in cup drawing assemblies having no space for inclusion of conventional strippers in addition to the draw die.

In practicing my invention, I attain the foregoing and other objects by providing in a uniquely constructed single unit the combination of a die for drawing cup-like pieces, typified by ammunition primer cups, and means thereafter effective for positively stripping the draw pieces from the punch. One preferred form of this apparatus specially adapted for the processing of primer cups will herein be described and illustratively shown by the accompanying drawings wherein:

Fig. 1 is a sectional view showing a blank which has been preliminarily cupped emerging from a blanking and cupping die preparatory to being forced by the draw punch down through my novel combination die and stripper;

Fig. 2, representing an advanced stage of the Fig. 1 operation, shows the partially formed primer cup passing through my unique dual acting die and stripper;

Fig. 3 is a familiar view which shows the head of the fully drawn cup being flattened by contact with a backing punch;

Fig. 4 progressively represents how the drawn cup returns to contact an underside of my new type drawing die as the draw punch is withdrawn upward;

Fig. 5 further illustrates the upward withdrawal of the draw punch and the unique cocking action of my "floating" dual purpose die which causes the draw piece to abut thereagainst;

Fig. 6 shows the finished primer cup, which was stripped from the draw punch by contact

2

with the under side of the "floating" die in Fig. 5, being evicted from the machine;

Fig. 6 parallels the Fig. 5 view with the exception that a primer cup which has failed to strip on the bottom edge of the die is shown wedged within the bore of the cocked floating die to thereby become positively stripped from the draw punch;

Fig. 8 is a bottom view of the combined floating die and stripper which is shown mounted in a die-holder in Figs. 1 to 7, illustrating the portion of the die's under surface which is specially ground obliquely to the central bore axis of the die;

Fig. 9 resembles the foregoing sectional representations but includes an alternate form of my superior dual acting die and stripper unit.

Conventional primer cup drawing apparatus and method

The drawing of cup-like tubes by means of the punch and die method is well known to the prior art. Such procedures have long been used in manufacturing cartridge cases, primer cups and the like.

In the course of drawing metal tubes or cups through a die, the drawn objects tend to adhere to the draw punch. It then becomes necessary to remove, or as is popularly termed "strip," the draw piece from the punch.

In deep drawing, as exemplified by cartridge cases, special stripping devices have been incorporated within a drawing mechanism assembly in order to accomplish this removal of the draw piece. An example of one such conventional stripping means is represented by Patent 2,327,936 which was issued on August 24, 1943 to Raymond E. Slater for "Tube Drawing Apparatus."

In certain drawing operations well typified by primer manufacturing procedures, it is sometimes impractical to use stripping means in supplement to the normal drawing dies because of a lack of sufficient space in the mechanism by which the draw piece is fabricated. In lieu of such separate stripping devices, the prior art has depended upon the draw die itself to effect the required stripping action.

As the drawn object returns upward adhering to the draw punch, it is expected that the draw piece, relieved of the stress exerted by the die as the primer cup or other object is being passed therethrough, will expand to a sufficiently large overall diameter to thereby cause it to contact the bottom edge of the draw die's central bore.

This contact will stop further upward movement of the draw piece and thus cause the desired stripping action as the draw punch continues its ascension. This conventional type of stripping mechanism and procedure is shown and described in my Patent 2,379,450 for "Primer Manufacture" which was issued on July 3, 1945.

However, when utilizing such conventional dies for stripping the draw piece, extreme care must be exercised to maintain the sharpness of the bottom edge and the diameter of the lowermost portion of the draw die's central bore. If this lower opening of the central bore is permitted to become bellmouthed, or its bottom edge rounded, sufficient resistance may not be exerted on the draw piece to positively strip it from the punch.

In cases where reliance is placed upon a stationary drawing die to strip the draw piece, as in Patent 2,379,450, trouble oftentimes arises when the side walls of the drawn object have failed to spread sufficiently to assure contact with the die when the frictionally held draw piece returns upward along with the draw punch. This failure results in the finished draw piece penetrating and occupying space within the draw die and thereby interfering with the succeeding drawing operation, consequently causing the mechanism to become jammed.

The described lack of positive stripping action in the prior art devices has caused a distinct need for my herein disclosed improvement. As will now be made clear, my unique combination die and positive acting stripper fulfills this need and has made possible trouble-free manufacture of even the very smallest ammunition primer cups and the like.

My improved combination die and stripper

My unique dual-acting die can be made quite easily from available bar stock or by altering the form of a conventional ring-shaped drawing die. First, the entire top or input surface is machined at an oblique angle (see Figs. 1 to 7) with respect to the vertical axis of the die's central bore. Next a central portion of the die's under or output surface including the area surrounding the central bore (see Fig. 8) thereof, is likewise machined obliquely and parallel to the just described machined upper surface. The result achieved is depicted by the novel die form shown at 16 in Figs. 1 to 8.

The thus designed dual purpose die 16 is placed in a conventional die holder 17 in the customary manner. In the arrangement shown by the accompanying illustrations the assembly includes a conventional blanking and cupping die 18 also maintained within the die holder 17, both dies being held therein by the die holder plate 19. This die holder plate 19 is fastened to the die holder 17 by screws (not shown in the illustrated sectional views).

For purposes of completeness of illustration Fig. 1 of the drawings shows a blanking punch 20 which stamps out blanks from the stock 25 being fed through channel 26 in die holder plate 19. The complete operation, represented here only in part, is best shown and thoroughly described in my earlier mentioned Patent 2,379,450 for "Primer Manufacture." There I have described the manner in which, by means of a double acting press, one revolution of a crankshaft (not here shown) blanks and forms the cup here represented in Fig. 1 by 27A.

My herein disclosed improvement comprises

the unique die 16 which may readily be substituted for prior art sizing or redrawing dies (see reference character 3 in Patent 2,379,450) to effect immediate improvement in the conventional manufacture of primer cups and similar objects. For a thorough understanding of this novel die's function, the following description need, therefore, only be confined to the essential parts coacting therewith.

Operation of my unique combination die and stripper

As Fig. 1 shows, the draw piece has been formed into a cup 27A by passage through a conventional cupping die 18, this having been effected by the downward force of draw punch 30. The drawn cup 27A then enters the central bore 32 of die 16 which is aligned directly therebeneath and whose inner side walls parallel the vertical axis of the draw punch 30.

Continued downward movement of punch 30 from the Fig. 1 position forces the cupped draw piece 27A through die 16 to take the form shown at 27B in Fig. 2. In the illustrated mechanism, which is designed for manufacturing flat bottom primer cups, punch 30 carries the draw pieces into contact with a backing punch 34, as shown in Fig. 3, giving the drawn cups the final shape represented by 27C.

With continued rotation of the machine's crankshaft (not here shown) draw punch 30 is made to ascend. In so doing the completed draw piece 27C, being frictionally held to draw punch 30, also is raised upward. If the side walls of the completed draw piece 27C have spread apart sufficiently, as normally occurs when a cup is relieved from the stress of being forced through a drawing die, this raising of the drawn cup will bring it into contact with the under side of the die 16, as shown in Fig. 4.

Such contact will generally cause the drawn cup 27C to be stripped from draw punch 30 even by a conventional draw die, and the same holds true with my improved combination die and stripper 16. However, although the resultant stripping action is similar in both the old and the new types, the manner of operation is different. Whereas, moreover, the conventional and my new dies both can strip drawn cups under the just described conditions, it will later be brought out that my improvement will function in certain cases where the prior art device fails to operate properly.

As shown in Fig. 5, when my novel die 16 is contacted by the ascending drawn cup 27C it is cocked upwardly until restrained by the immovable cupping die 18. Since the draw piece 27C is then prevented from further ascension, the rising punch 30 is withdrawn free of engagement therewith. The thus stripped draw piece is then ejected from the machine by any conventional method such as by a blast of air as used in Patent 2,379,450 and here represented in the accompanying illustrations by the directional arrows shown in Fig. 6.

The superiority of my novel dual acting die resides in its ability to strip cup shaped objects that have failed to contact and be stripped by the under side of the draw die. The ability to strip those draw pieces which would normally return through a conventional stationary type die gives to my novel die the ability to act as a completely positive stripper, unlike its predecessors in the art.

Reference to Fig. 7 will show the manner in

which these undersized draw pieces 27D are stripped by my novel combination die and stripper 16. The drawn cup 27D is there shown to have penetrated up into die 16's central bore 32 due to frictional adherence of the cup to the ascending punch 30. The draw piece, being of diameter approximately equal to the central bore 32 through which it was drawn, is caused to strike the side walls of that bore. Only very slight contact is necessary to cause die 16 to cock upwardly until it is stopped by the blanking and cupping die 18 as shown in Fig. 7.

The just described cocking action brings a portion of central bore 32's upper side wall and, diametrically opposite thereto, a portion of that bore's lower side wall closer than normal to the draw punch 30. This inward movement of central bore 32's opposing sidewalls with respect to the draw punch diminishes the cross sectional area of central bore 32 available for upward travel of draw piece 27D. The result is that an edge of the cup-like draw piece's open end becomes wedged against the inwardly protruding upper wall portion of die 16's central bore 32, while at the same time the opposite side of the draw piece is pinned against the lower wall portion of bore 32 which has moved in towards punch 30.

The higher up the drawn cup 27D rises, the tighter it becomes wedged against the die's inner walls. This wedging action holds the draw piece as the ascending punch 30 is withdrawn therefrom. Once the draw piece is so released from the draw punch, die 16 drops down from its cocked Fig. 7 to the Fig. 1 position preparatory to receiving and acting upon another cupped blank 27A. Simultaneously draw piece 27D may be ejected as was drawn cup 27C in Fig. 6, if the draw piece is not wedged too tightly within the die's bore. If the draw piece remains wedged within the die, however, it is ejected by the next piece that is drawn through the die.

Alternate form of my novel die and stripper

It will be evident to those skilled in the art that my unique die and stripper unit may be used in somewhat different forms than heretofore shown and described, and in fact may be applied to other uses than in the manufacture of primer cups. One such substitute form is shown at 16A in Fig. 9 and will now be described.

To make this particular form of my improved dual acting die, the entire upper and lower surfaces of a conventional die (not shown) or bar stock material are ground parallel to each other, both at an oblique angle with respect to the vertical axis of the die's central bore. This grinding of the entire bottom surface, rather than merely grinding a portion surrounding the central bore 32A as in the method described for manufacturing my new type die 16, may possibly be a more preferable manner of practicing my invention for some sizes of dies than the earlier representation because it may be simpler to make.

To utilize this form of my improvement, however, a slight modification to die holder 17 is required, namely, an angularly inclined supporting shelf 38, which must be inserted or built into the die holder 17 and the die 16A keyed against rotation by some means as the pin 40 shown in Fig. 9. This shelf 38 enables the alternate design die 16A to assume the same relative positions as my first represented novel die 16 before and during the drawing operation, while still leaving the necessary room for the earlier de-

scribed cocking movement that makes my improved die an absolutely positive stripper for the cups which are drawn therethrough.

Summary

From the foregoing description and accompanying illustration it will have become evident that my improved combination die and stripper is capable of performing a dual function of drawing cup-like pieces and thereafter acting in a unique manner as a positive stripper to remove the draw piece from the drawn punch; that my invention has eliminated the need for separate stripping means in supplement to normal punch and die apparatus by which such cup-like pieces are made; and that I have provided means for stripping draw pieces from the punch in cup drawing assemblies having no space for inclusion of conventional strippers in addition to the draw die.

It will be evident to those skilled in the art that my improvement is not limited in its application to the manufacture of ammunition primer cups which is here shown and described for purposes of explanation, but may properly be utilized in other punch-and-die drawing operations without departing from the spirit and intent of the invention.

My inventive improvements are therefore extensive in their adaption and are not to be restricted to the specific form here disclosed by way of illustration.

I claim:

1. In apparatus for forming cup-shaped tubular members, the combination of a die holding structure comprising substantially parallel first and second interior wall surfaces spaced one from the other and having substantially coaxial openings extending therethrough, a reciprocable draw punch axially movable forwardly and backwardly through said holding structure openings, and a die positioned between said first and second wall surfaces with its input end on the first surface side and there so supported by said holding structure as normally to rest its discharge end surface against said second wall surface with the bore axis of the die coinciding with the draw punch axis whereby during each advancing stroke of said punch a cup blank forced forwardly through the die by the punch will be drawn into a tubular member, the body of said die nearly filling the space between said first and second wall surfaces on one side edge of the die and tapering to a thinner section on the opposite side edge thereby freeing said thinner portion only of the die for limited backward travel which angularly tilts the die bore axis away from the drawn punch axis whereby during each backward stroke of said punch the open-end edge of said punch-carried tubular member in returning against the die's discharge end will tilt the die bore axis as aforesaid and thereby so block further backward movement of the tubular member as positively to strip same from the draw punch.
2. In apparatus for forming cup-shaped tubular members, the combination of a die holding structure comprising substantially parallel upper and lower interior wall surfaces spaced one from the other and having substantially coaxial openings extending therethrough, a reciprocable draw punch axially movable downwardly and upwardly through said holding structure openings, and a die positioned between said upper and lower wall surfaces with its input end uppermost and there so supported by said holding structure that

when normally resting on said lower wall surface before and during each down stroke of said draw punch the bore axis of said die coincides with the draw punch axis whereby a cup blank forced downwardly through the die by the punch will be drawn into a tubular member, the body of said die nearly filling the space between said upper and lower wall surfaces on one side edge of the die and tapering to a lesser thickness on the opposite side edge thereby freeing said thinner portion only of the die for limited upward travel which angularly tilts the die bore axis away from the draw punch axis whereby during each return up stroke of said punch the open-end edge of said punch-carried tubular member in 15 upwardly returning against the die's lower discharge end will tilt the die bore axis as aforesaid and thereby so block further upward movement of the tubular member as positively to strip same from the draw punch.

3. In a drawing punch and die apparatus, combined die and stripper means comprising a readily cocked member having a bore extending axially therethrough and having parallel first and second surfaces which are oblique with respect to the said bore's axis, a holder for said member having two spaced wall surfaces, means in said holder end coating therewith for holding one side of said member so that the member's opposing side may be cocked between the two 25 holder wall surfaces, and keying means in said holder for preventing lateral movement of said member without limiting its said cocking movement.

4. In apparatus for forming tubular members, the combination of: a die holder comprising a box-like structure formed of sidewalls and a base with an opening therethrough; a reciprocable draw punch axially movable through the opening in said holder's base; a tube drawing die having an input surface and an opposed output surface of which the entire input surface is substantially oblique with respect to the axis of the die's bore and the output surface is perpendicular to said bore axis except for an area encompassing the bore which is parallel to the die's input surface, the die being movably mounted in said holder so that during movement of said punch in the direction of the holder's base the die's output surface abuts against said holder's base while the die's input surface is out of perpendicular to the axis of the punch although the die's bore is in axial coincidence with the punch, whereby during each stroke of said punch in the direction of the holder's base a tube blank forced through the die will be drawn out; and a plate-like member having an opening therethrough for admitting said punch and secured to said holder so as to retain said die therein and yet provide room for the die to cock away from said holder's base so that the die's bore axis is tilted out of coincidence with the draw punch axis, whereby during each stroke of said punch away from said holder's base the leading edge of the punch-carried drawn tubular member will contact the die and tilt its bore axis as aforesaid and thereby so block further backward movement of the tubular member as positively to strip same from the draw punch.

5. The combination of claim 4 in which the die is essentially of a ring-shaped construction whose input surface is substantially oblique with respect to the axis of the die's bore and whose

output surface is perpendicular to the said bore axis.

6. The combination of claim 4 in which the die is essentially of a ring-shaped construction having opposed first and second surfaces of which the first surface is substantially oblique with respect to the axis of the die's bore and the second surface is perpendicular to said bore axis except for an area encompassing the bore which is parallel to said first surface.

7. In apparatus for forming tubular members, the combination of: a die-holder comprising a box-like structure formed of sidewalls and a horizontal base with a vertical opening therethrough; a reciprocable draw punch axially movable downwardly and upwardly through the opening in said tube holder's base; a drawing die having an upper input surface and an opposed lower output surface of which the entire upper

20 surface is substantially oblique with respect to the axis of the die's bore and the lower surface is perpendicular to said bore axis except for an area encompassing the bore which is parallel to the die's upper surface, the die being movably mounted in said holder so that during downward movement of said punch the die's lower surface abuts against said holder's base with the die's upper surface out of perpendicular to the axis of the punch but with the die's bore in axial coincidence with the punch, whereby during each downward stroke of said punch a tube blank forced through the die will be drawn out; and a plate-like member having an opening therethrough for admitting said punch and secured to said holder so as to retain said die therein and yet provide room for the die to cock upwardly so that the die's bore axis tilted out of coincidence with the draw punch axis, whereby during each upward stroke of said punch the leading edge of the punch-carried drawn tubular member will contact the die and tilt its bore axis as aforesaid and thereby so block further upward movement of the tubular member as positively to strip same from the draw punch.

8. In apparatus for forming tubular members, the combination of: a die-holder comprising a box-like structure formed of sidewalls and a base with an opening therethrough; a reciprocable draw punch axially movable through the opening in said holder's base; a first tube drawing die having a first surface which is substantially oblique with respect to the axis of the die's bore and an opposed second surface which is perpendicular to said bore axis except for an area encompassing the bore which is parallel to the die's first surface, the die being movably mounted in said holder so that during movement of said punch in the direction of the holder's base the die's second surface abuts against said holder's base while its first surface is out of perpendicular to the axis of the punch although the die's bore is in axial coincidence with the punch,

55 whereby during each stroke of said punch in the direction of the holder's base a tube blank will be drawn therethrough; and a second tube drawing die having opposed first and second surfaces the latter of which is perpendicular to the axis of the die's bore which is axially aligned with said punch, the die being secured within said holder so that its second surface confronts

60 and serves to contain said first die therein and yet provide room for said first die to cock away from said holder's base so that its bore axis is tilted out of axial coincidence with the draw punch axis, whereby during each stroke of said

75 punch, the die being secured within said holder so that its second surface confronts

punch away from said holder's base the leading edge of the punch-carried drawn tubular member will contact said first die and tilt its bore axis as aforesaid and thereby so block further movement of the tubular member as positively to strip same from the still moving draw punch.

9. In apparatus for forming tubular members, the combination of: a die-holder comprising a box-like structure formed of sidewalls and a horizontal base with a vertical opening therethrough; a reciprocable draw punch axially movable downwardly and upwardly through the opening in said holder's base; a first tube drawing die having opposed upper and lower surfaces of which the entire upper surface is substantially oblique with respect to the axis of the die's bore and the lower surface is perpendicular to said bore axis except for an area encompassing the bore which is parallel to the die's upper surface, the die being movably mounted in said holder so that during downward movement of said punch the die's lower surface abuts against said holder's base with the die's upper surface out of perpendicular to the axis of the punch but with the die's bore in axial coincidence with the punch, whereby during each downward stroke of said punch a tube blank will be drawn there-

through; and a second tube drawing die whose lower surface is perpendicular to the axis of the die's bore which is axially aligned with said punch, the die being secured within said holder so that its lower surface confronts and serves to contain said first die therein and yet provide room for said first die to cock upwardly so that its bore axis is tilted out of axial coincidence with the draw punch axis, whereby during each upward stroke of said punch the leading edge of the punch-carried drawn tubular member will contact said first die and tilt its bore axis as aforesaid and thereby so block further upward movement of the tubular member as positively to strip same from the draw punch.

CLARENCE WALTON MUSSER.
